UNITED STATES PATENT OFFICE.

ANDREW TURNBULL, OF SANTA ANA, CALIFORNIA.

SANITARY GARBAGE CAN.

Application filed January 19, 1926. Serial No. 82,192.

My invention is a sanitary garbage can or the like adapted to contain a disinfecting fluid in the cover which may be injected into the can and a closure bottom which may be latched closed and unlatched to swing open and allow ready dumping of the garbage without removing the cover.

An object of my invention is in the construction of a sanitary garbage can in which the cover is provided with a liquid container preferably having upper and lower walls. A trap type of valve is utilized in the lower wall operated by a pressing plunger so that on depressing the plunger a certain amount of liquid is trapped at the outlet passage and thus allowing a limited amount to pass into the can.

A further feature of my invention is in the adjustable characteristics of the trap valve so that a varied amount of liquid may be passed from the container into the can.

In regard to the bottom closure I preferably hinge the bottom of the can to one side and have a pivoted latch on the opposite side of the can body, this latch operating to hook the base or bottom of the can closed and to allow unlatching so that the contents may be readily dumped without removing the cover or lid.

My invention will be more readily understood from the following description and drawings, in which:

Figure 1 is a side elevation of my sanitary garbage can. This however, indicates the cover with a liquid container of larger size than is usually necessary.

Fig. 2 is a vertical cross section through the can.

Fig. 3 is a top plan view taken in the direction of the arrow 3 of Fig. 1.

Fig. 4 is an enlarged view of the latch for unlocking the hinged bottom as if taken in the direction of the arrow 4 of Figs. 1 and 2.

The structure for containing disinfecting fluid is substantially as follows, being illustrated particularly in Figs. 1 and 2:

The can body 1 has a plain upper rim 2 as is the usual practice, on which is fitted a cover 3. The can and the cover are usually made circular, the cover having a top 4 and a depending skirt 5 forming a tight fit over the upper end of the can. A transverse partition 6 is inserted in the skirt portion parallel to the top and forms a liquid containing chamber 7. An inlet pipe 8 with a cap 9 is utilized to fill the container and a dis-

charge valve 10 is utilized to discharge the liquid into the garbage can for disinfecting.

The valve structure is made substantially as follows:

The partition 6 is provided with an internally threaded hub 11 in which is threaded an annular valve seat 12 having a circular opening 13 through which extends a valve plunger 14. This plunger is threaded for part of its length and has a lower rubber washer 15 held in place by an abutment nut 16. An upper rubber washer 17 is held in place by an upper abutment nut 18. These nuts are adjustable towards and from each other and the washers are adapted to act as valve members on opposite sides of the valve seat 12.

A tubular stem 19 extends upwardly from the top of the cover and has an opening therethrough forming a slide for the plunger. This stem is externally screw threaded and is engaged by a packing nut 20 having a liquid-tight packing gland 21 therebetween. An inverted cupped sleeve 22 is screw threaded on the upper end of the valve plunger and has a lock nut 23 inside thereof, this nut forming an abutment for the compression spring 24 and is tensioned between the packing nut 20 and the lock nut 23 and therefore tends to force the plunger upwardly, hence closing the washer 15 against the lower face of the valve seat.

A bracket 25, preferably made of sheet metal extends upwardly on opposite sides of the valve stem and has a cross member 26 with a circular opening 27 in which the cupped sleeve slides, forming a guide for same.

The operation of the garbage can for injecting a disinfecting fluid into the can is substantially as follows:

The disinfectants usually used are of rather a thick consistency and do not flow readily and as the valve plunger is normally drawn upwardly the outlet is positively closed. A small amount of liquid however, is contained in the circular opening 13 of the valve seat around the plunger and on depressing the plunger by pressure on the top of the cupped sleeve 22, the washer 17 sets on the upper side of the valve seat 12, thereby preventing outflow of liquid from the container. Thus the amount trapped below the washer 17 drops into the can. This is usually only a few drops as the plunger is operated quickly and is sufficient

to disinfect the can after insertion of the garbage. However, if desired, the plunger may be pressed downwardly a number of times to inject more or less disinfecting material.

5 The dumping bottom construction is substantially as follows:

The lower end of the can is completely open, being closed by a hinged bottom 30 which forms a tight fit and is preferably made with an inwardly turned flange 31 having a slight inward bevel as shown in Fig. 2. This bottom is secured to the can wall by a hinge 32 on one side. A hook 33 extends 15 upwardly from the opposite side of the bottom and has a lateral projection 34.

A swivelled latch 35 has a handle 36 and a laterally extending tongue 37 on the opposite end to engage the projection 34 of the 20 hook. This latch is preferably pivoted on a pivot pin 38 which extends through a circular reinforcement 39 of the can body.

The usual handle 40 is fastened on the eyes 41 on opposite sides of the can body.

25 In the operation of discharging the can it is merely necessary to elevate the can over the receptacle to receive the contents and operate the latch by means of the handle 36 to disengage same from the hook 33 and if 30 the weight of the contents of the can is insufficient to swing the bottom open the foot may be pressed on the projection 34 to swing the bottom open.

From the above construction it will be 35 seen that I have provided a sanitary garbage can in which a liquid may be injected as desired to disinfect the garbage in the can. The cover containing the liquid is of such design that it may be adapted to standard 40 garbage cans and may be marketed as a unit for use with cans now on the market. However, it is desirable that the cover with the liquid container therein be incorporated in the can having my discharge arrangement 45 of hinged bottom so that in the collection of garbage it is not necessary for the people handling same to remove the cover which usually becomes more or less damaged in careless handling.

50 It is obvious that my can in its characteristics as having a container for a sanitary

liquid and having a self-dumping bottom may be considerably changed in general construction and in specific details without departing from the spirit of my invention as 55 set forth in the description, drawings and claims.

Having described my invention, what I claim is:

1. A cover for a sanitary garbage can 60 comprising in combination a top wall having a depending substantially circular skirt, a partition across the skirt forming a container above the partition, a valve seat threaded in the partition, a tubular stem secured to the top, a valve plunger slidable through the stem and through the valve seat there being an annular space between the stem and the seat, a valve washer below the seat secured to the plunger, a second valve 65 washer above the seat secured to the plunger, a packing nut secured to the tubular stem, a bracket secured to the top having a cross member with a hole therethrough, a cupped sleeve secured to the upper end of 70 the plunger slidable through said opening and over the packing nut and a compression spring between the cupped sleeve and the said packing nut.

2. A garbage can having a can cover with 80 a top, side walls, a partition across the side walls and a depending skirt, there being an opening through the top, a valve plunger slidable therethrough, there being a circular opening through the partition, the 85 plunger extending therethrough and having washers secured to same on the inside and outside of the partition to form valve closures, a tubular stem secured to the top through which the plunger passes, a 90 packing nut secured to the tubular stem, a bracket secured to the top having an opening with a cupped sleeve extending therethrough, the upper end of the plunger engaging the upper portion of said sleeve, and 95 a spring coiled around the plunger bearing against the upper end of same and the packing nut.

In testimony whereof I have signed my name to this specification.

AND. TURNBULL.
